ATTORNEY

UNITED STATES PATENT OFFICE

JAMES W. HOWELL, OF CLEVELAND, OHIO, ASSIGNOR TO THE WHITE MOTOR COMPANY, OF CLEVELAND, OHIO, A CORPORATION OF OHIO

ELEVATING MECHANISM

Application filed March 21, 1928. Serial No. 263,308.

This invention relates to elevating mechanism.

An object of this invention is to provide an elevating mechanism comprising a movable element, which maintains a constant angular relation to the base of the mechanism.

Another object of this invention is to provide a wheeled elevating mechanism having a base in the form of a small truck or dolly.

Another object of this invention is to provide an elevating mechanism of simple, durable and efficient construction.

Other objects will hereinafter appear.

The invention itself will be more readily understood from the description of one practical embodiment thereof, illustrated in the accompanying drawings in which:

Figure 1 is a plan view of a device embodying the present invention, certain elements being broken away in the interest of clarity.

Figure 2 is a side elevational view of the structure illustrated in Figure 1.

Figure 3 is a perspective view, partly in section, illustrating one of a number of alternative elements that may be used in conjunction with the elevating mechanism shown in Figures 1 and 2, and

Figure 4 is a perspective view of a second alternative element adapted for use with the elevating mechanism.

The device illustrated is designed for use in the assembly of automotive vehicles, such as automobiles and the like, and is made small enough to pass between the wheels and under the frame of such vehicles. It may be used, as will presently become apparent, both to carry the work (heavy parts of the vehicle such as a transmission) to the place of assembly and to elevate the same to a position for attachment.

Referring to the drawings in which like parts are designated by like reference numerals, the device comprises a base in the form of a small truck or dolly. This base is rectangular in outline and consists of side members 1, end member 2 and wheels 3 journaled on cylindrical extension 4 formed on end members 2. Mounted at one end of the base and secured to the side rails 1, there is a

pair of vertically disposed gusset plates 5 upon which is rotatably mounted a pair of levers or links 6 by means of bolts 7. Connecting the side rails 1, and extending through both the side rails 1 and the gusset plates 5, is a tie rod 8 whose axis falls within the same vertical plane as the axes of the bolt 7. Rotatably mounted upon the tie rod 8 is a pair of levers or links 9 spaced apart into loose contact with the plates 5 by means of a sleeve 10, which surrounds the intermediate portion of the tie rod 8. The two pairs of levers 6-6 and 9-9 are pivotally connected at their outer ends to a socket member 12 by means of bolts 13 and 14 respectively, and since the distance between bolts 7 and 13 is made equal to the distance between tie rod 8 and bolt 14, and the distance between bolt 7 and tie rod 8 is made equal to the distance between bolts 13 and 14, these levers form two sides of a parallelogram. The socket member 12 forms a third side of the parallelogram and when raised or lowered in a manner to be hereinafter described, remains parallel to the fixed fourth side of the parallelogram which for the present purpose may be considered as a vertical line passing through the axes of the bolts 7 and the tie rod 8.

Above the bolts 7 and intermediate the plates 5 there is a pivotally supported bar or cross member 15. This bar, as illustrated, is provided with trunnions 16, adjacent its terminating ends which trunnions are journaled in aligned apertures in the upper portion of plates 5. In the central portion of the bar 15 is a transversely disposed bore 17, which provides a mounting for a shaft 18, the shaft being longitudinally sustained therein by a head 19. Formed upon the free end of the shaft is a collar 20 which abuts the inner face of the bar 15 and which is secured in locking engagement to the shaft by a set screw 21. The rear end of the shaft 18 is screw threaded through an aperture 22 formed in a transverse member 23 which extends between levers 9 and is connected thereto by trunnions 24 journaled in bearing apertures forming said levers.

To prevent distortion of the levers 6, par-

ticularly such distortion as would affect the free rotation of the transverse member 23, the levers are provided with a tie rod 25 and a spacer sleeve 26, which are preferably positioned adjacent the cross member 23.

As will be readily seen, the longitudinal member 18 forms an adjustable link connecting the fixed plates 5 with the movable levers 6, and when turned by means of an operating handle 27 mounted in the enlarged head 10 of the member 18, effects angular movement of the levers 19, about their respective fixed pivots, 6 and 9, (bolts 7 and tie rod 8) which movement will raise or lower the socket member 12, depending upon the rotational direction in which the member 18 is turned.

The socket member 12 is provided with an aperture 28 preferably rectangular in cross section and partially closed near its bottom 20 end by a removable bolt 29, the side walls of which are formed parallel to the normally vertical fourth side of the parallelogram, hereinbefore described.

Referring now to Figures 3 and 4 which 25 illustrate two of a number of tools that may be used in conjunction with the truck's elevating mechanism; the tool illustrated in Figure 3 comprises a member 30 of rectangular cross section adapted to be inserted with- 30 in the aperture 28, and a work supporting platform 31 rotatably mounted on the upper end of member 30 by means of a pin 32. The tool shown in Figure 4 has the form of a right angle bell crank of rectangular cross 35 section, whose lower arm 33 is adapted to fit within the aperture 28 and whose upper arm 34 is provided with an aperture 35 adapted to receive means for attaching the work thereto.

It is obvious from the foregoing description, that the platform 31 of the tool illustrated in Figure 3 and the upper arm 34 of the tool illustrated in Figure 4 will retain a horizontal position for any angular position of the levers 6-6 and 9-9, and that work placed in a stable position upon the platform 31 will retain its original angular relation to the horizontal during elevation or depression.

While I have described the illustrated embodiment of my invention in some particularity, obviously many variations and modifications thereof will readily occur to those skilled in the art to which it appertains, I 55 do not, therefore, limit myself to the precise details shown and described, but claim as my invention all embodiments coming within the scope of the appended claim.

What I claim is:

The combination with a dolly comprising a platform, of an elevating mechanism comprising a pair of spaced links of equal length pivotally connected to said dolly at spaced points, a third link in the form of a tool holder having a length equal to the distance

between said points and connecting the free ends of the first named links in the order of their attachment to said dolly, a fourth link in the form of a screw pivotally attached to and connecting said dolly and one of said first named links, the point of attachment of said fourth link to said dolly being a substantial distance above the platform of said dolly, and an operating handle on said fourth link adjacent the aforesaid point of attachment.

In testimony whereof I hereunto affix my signature this 5th day of March, 1928.

JAMES W. HOWELL.
